[57] CLAIM

The ornamental design for a communications headset, as shown and described.

DESCRIPTION

FIG. 1 is a perspective view of a communications headset showing our new design;

FIG. 2 is a left view taken of FIG. 1;

FIG. 3 is a front elevational view thereof;

FIG. 4 is a back elevational view thereof;

FIG. 5 is a top plan view thereof;

FIG. 6 is a right elevational view thereof;

FIG. 7 is a bottom plan view thereof; and,

FIG. 8 is a side view of the design illustrating how it is typically worn on the ear.

The broken line showing of the microphone on FIGS. 1-8 and the human head on FIG. 8 is for illustrative purposes only and forms no part of the claimed design.
